UNITED STATES PATENT OFFICE.

GEORGE FREDERICK TAYLOR AND HENRY ROCHEFORT, OF KINGS HEATH, NEAR BIRMINGHAM, ENGLAND.

GRINDING-MACHINE.

No. 914,763.

Specification of Letters Patent. Patented March 9, 1909.

Application filed June 9, 1908. Serial No. 437,579.

To all whom it may concern:

Be it known that we, GEORGE FREDERICK TAYLOR and HENRY ROCHEFORT, subjects of Great Britain, residing at 62 Cambridge road, Kings Heath, near the city of Birmingham, England, have invented new and useful Improvements Relating to Grinding Machines, of which the following is a specification.

10 This invention relates to machines for grinding metal articles accurately to the required dimensions and has for its object to construct an improved machine of the type in which the size of the finished work pieces 15 is unaffected by variations in the diameters of the grinding disks caused, for instance, by wear.

Referring to the two accompanying sheets of explanatory drawings:—Figure 1 is a 20 diagrammatic side elevation of a trip device constructed in accordance with this invention. Figs. 2 and 3 are respectively part 25 sectional plan and front elevation showing diagrammatically to a smaller scale than Fig. 1 a machine having our invention applied thereto.

The same reference characters in the different views indicate the same parts.

In a machine for grinding parallel shafts 30 or spindles as illustrated, a pair of trip devices are employed, one for diminishing the feed and the other for arresting the same. Such trip consists of a bell crank lever *a* and a pivoted stop or abutment piece *b* 35 mounted on a slide *c* which is adjustable by means of a suitable screw with respect to a bracket *d* secured to the bed or the slide of the machine. One end of the bell crank lever *a* is connected to a rod *e* which is itself 40 connected to an abutment lever *f* for operating a clutch of a suitable feeding mechanism as hereinafter described. The other end of the bell crank lever rests when the apparatus is set, against the end of the pivotal 45 stop as shown. For feed changing the first trip is so adjusted with respect to the work piece as *g* that when the diameter of the work approaches the finished size the periphery of the grinding disk *h* touches 50 the stop *b* and rotates the same about its pivot. The bell crank lever is thus released and the rod *e* aforesaid under the influence

of a spring *i* acting on the lever *a* is raised and so caused to lower the abutment lever *f* into position for operating the clutch above 55 referred to. For stopping the feed, the second trip is so adjusted that the disk *h* touches it as soon as the work piece is ground to the finished diameter. The lever *f* of this trip may either be adapted to 60 actuate the same clutch as the corresponding lever of the first trip and move the clutch into an inoperative position for stopping the feeding mechanism, or it may be arranged to act upon an independent feed 65 arresting clutch.

To avoid abrasion of the pivotal stops *b* by the grinding disk, each stop is fitted with a diamond *j* or other exceedingly hard material on which the grinding disk has no 70 appreciable action. Contact between the stop and disk is effected through the medium of the diamond or the like.

The feeding mechanism consists in one 75 convenient form of two trains of wheels *k* and *l* arranged through the medium of shafts *m* and *n* in conjunction with a feeding screw *n'* of the grinding disk slide. On the shaft *m* there is also mounted a hand wheel *o*. The wheel trains are proportioned 80 to give either a coarse or a fine feed. At the end of each reciprocatory motion or traverse of the work with respect to the disk, or vice versa, an operative movement is given to the feed mechanism by means of 85 a convenient ratchet *p* and pawl *q* operated by a spring controlled tappet or plunger *r*. Motion is given to the plunger by a lever *s* on the shaft *t* which also carries a striking lever *u*. The latter is engaged at the end 90 of each traverse by one or the other of the adjustable stops *v*. Either of the wheel trains *k* and *l* can be connected by means of a clutch *w* to the shaft *x* which receives motion from the ratchet shaft *y* through the 95 wheels *z*.

During the initial stages of the grinding operation the clutch is in the position shown with the coarse speed train *k* in action. On the actuation of the first trip mechanism the 100 lever *f* thereof is put into position for operating (on the next traverse of the slide) a lever *2*. With the movement of the said lever the clutch is carried into engagement

with the fine feed train *l*. On the operation of the second trip the corresponding lever *f* is lowered so that on the succeeding movement of the slide the lever *3* is acted upon 5 and the clutch is moved into its central or inoperative position where neither of the feed trains are engaged.

- For traversing the work slide any convenient and suitable mechanism may be employed, for example, a rack *4* operated by a wheel *5* which can be actuated by hand from a wheel *6*, or automatically by bevel wheels *7, 8, 9* and *10*, from the pulleys *11*. To reverse the direction of traverse one 15 or other of the wheels *8* and *9* is geared with the wheel *7*. The required movement of the said bevel wheels *8* and *9* is obtained at the end of each traverse of the slide by levers *12* and *13*, connected as shown to the lever *u*. 20 When the latter is moved by one of the stops *v* the ratchet is operated and simultaneously the motion of the slide is reversed. Effective operation of the wheels *8* and *9* is insured by the spring of the plunger *r*, for after the 25 lever *s* has just passed the apex of the plunger the recovery of the spring causes the movement of the lever *s* and its associated mechanism to be completed. With the operation of the clutch lever by the lever 30 *3* the levers *12* and *13* are also actuated owing to the abutment of the said lever *3* against a lever *14* on the shaft *t*. By the engagement with the lever *3* of a snug *15* on the lever *14* the motion of the levers *12* and 35 *13* is arrested when the wheels *8* and *9* are in the mid or inoperative position. Consequently the feeding and traversing mechanism are both stopped simultaneously. Any ordinary form of live and back centers. 40 or puppets as *16* and *17* may be adapted for supporting and rotating the work.

A machine constructed as hereinbefore described enables work of uniform accuracy to be obtained independently of wear 45 or variations arising from other causes in the diameters of the grinding disks and also enables such results to be produced consistently, as the mechanism employed is reliable and not readily deranged or thrown 50 out of order as in the case where electrical controls or stops are provided.

Having thus described our invention what we claim as new and desire to secure by Letters Patent is:—

- 55 1. In grinding machines, the combination with the grinding disk, and lateral and transverse feeding mechanism, of a pivoted stop arranged for actuation by the disk, a bell crank lever in contact with said stop, 60 and a mechanical feed controlling device operated with the movements of the said lever, substantially as set forth.

2. In grinding machines, the combination with a grinding disk, and lateral and trans-

verse feeding mechanism, of a pivoted stop 65 arranged for actuation by the disk, a bell crank lever in contact with the stop, an abutment lever, a bar connecting the said levers together, and mechanical means for operating the feeding mechanism from the 70 abutment lever, substantially as set forth.

3. In grinding machines, the combination with a grinding disk, and lateral and transverse feeding mechanism, of a pivoted stop arranged for actuation by the disk, a bell 75 crank lever in contact with the stop, an abutment lever, a bar connecting the said levers together, an adjustable slide on which the bell crank lever and stop are mounted, and mechanical means for operating the 80 feeding mechanism from the abutment lever, substantially as set forth.

4. In grinding machines, the combination with a grinding disk, and lateral and transverse feeding mechanism, of a pivoted stop 85 arranged for actuation by the disk, a bell crank lever in contact with the stop, an abutment lever, a bar connecting the said levers together, a spring whereby the said levers and rod are operated on the actuation of the stop by the grinding disk, and mechanical means for operating the feeding mechanism from the abutment lever, substantially as set forth.

5. In grinding machines, the combination 95 with a grinding disk, and lateral feeding mechanism, of a transverse feeding screw, a pair of wheel trains in conjunction with the screw, a ratchet and pawl operated from the lateral feeding mechanism, a 100 clutch whereby either of the wheel trains is put into connection with the screw, a clutch lever, a pivoted stop arranged for actuation by the grinding disk, and actuating mechanism for the said clutch lever, said mechanism being held out of action by the stop and liberated when the stop is operated by the disk, substantially as set forth.

6. In grinding machines, the combination with a grinding disk, and transverse feeding mechanism, of a rack and pinion, reversing bevel wheels in conjunction with the said pinion, actuating levers for the said bevel wheels, operating stops for the said levers, a pivoted stop arranged for 110 actuation by the grinding disk, and means for arresting the actuating levers of the reversing wheels, said means being held out of action by the pivoted stop and liberated when the stop is operated by the grinding 115 disk, substantially as set forth.

7. In grinding machines, the combination comprising a reciprocating work supporting bed, a grinding disk laterally movable with respect to the work supporting bed, a 125 pair of pivoted stops mounted on the said bed and arranged for actuation by the grinding disk, feeding mechanism for

traversing the disk toward the work supporting bed and the latter across the disk, and controlling means for the said mechanism, said means being held out of action by the pivoted stops and liberated when the stops are operated by the disk, substantially as set forth,

In testimony whereof we have signed our

names to this specification in the presence of two subscribing witnesses.
